UNITED STATES PATENT OFFICE.

JOHN M. C. HOWELL, OF MASCOT, TENNESSEE.

MAIL-BAG CRANE.

SPECIFICATION forming part of Letters Patent No. 739,876, dated September 29, 1903.

Application filed May 7, 1903. Serial No. 156,119. (No model.)

To all whom it may concern:

Be it known that I, JOHN M. C. HOWELL, a citizen of the United States, residing at Mascot, in the county of Knox and State of Tennessee, have invented a new and useful Improvement in Mail-Bag Cranes, of which the following is a specification, reference being had to the accompanying drawings.

My invention relates to that class of mail-bag cranes designed to be located adjacent to a railway-track and hold a mail-bag suspended vertically in proper position for engagement and removal by an arm projecting laterally from a mail-car passing the point at which the crane is located.

The object of my invention is to produce a mail-bag crane which is simple and may be constructed at small cost and which is at the same time durable and convenient and reliable for operation.

My improved construction makes possible the convenient vertical and radial adjustment of the arms which support the mail-bag and permits the hanging of the bag by a person standing on the ground and without the use of a ladder or other means for climbing to the height at which the bag rests when in position to be taken by the train. To this end the bag-supporting arms and the parts to which they are directly connected are vertically shiftable, their upward movement being effected manually when the bag has been attached to the supporting-arms, and their descent being automatically effected directly after the bag has been removed. My improved construction also makes possible the ready removal of all the operative parts from the supporting post or mast.

In the accompanying drawings, Figure 1 is a side elevation of a crane embodying my improvement and holding a mail-bag in proper position to be taken by the mail-car, the view being parallel to the railway-track. Fig. 2 is an elevation looking transversely across the track or toward the left as the crane is shown in Fig. 1, the bag having been discharged and the supporting-frame having made a quarter-rotation upon the mast and descended upon the latter a distance nearly equal to the length of said frame. Fig. 3 is a plan of the crane, the supporting-frame being in the position shown in Fig. 2. Figs. 4

and 5 are detail views illustrating constructions for resisting the movement of the supporting-frame when the latter is in its elevated position.

Referring to said drawings, 1 is a vertical rigid post or mast having its lower end secured in any suitable manner, as by insertion into the earth or a base of stone. Said mast may be of wood, but it is preferably made of metal, and it is preferably cylindrical. A supporting-frame 2 is arranged to reciprocate vertically and rotate upon said mast. Said frame may be of any suitable form. Its essential features are means for guiding said frame for vertical and rotary movement and a pair of arms for engaging the mail-bag A. The drawings show said frame consisting of the upper cross-piece 3, the lower cross-piece 4, two vertical bars rigidly connecting the cross-pieces 3 and 4, an upper arm 6, and a lower arm 7. The mast extends loosely through each of the cross-pieces 3 and 4. This allows said frame to slide up and down and also rotate upon said mast. The upper arm 6 is an extension of said frame, and it is preferably rigid. The drawings show said arm clamped to the upper face of the cross-piece 3 by means of a nut 6^a, applied to the upper end of the adjacent bar 5. Said bar may, however, be secured in any suitable manner. It might, for instance, be a continuation of the cross-piece 3. The lower arm 7 is made yielding in a vertical plane, preferably by hinging it. The drawings show said arm hinged at 8 to the lower cross-piece 4 in such manner as to permit the outer end of said arm to move downward by gravity when released by the removal of the mail-bag. It will be understood, however, that said arms 6 and 7 may be otherwise made relatively yielding, so that their outer ends will tend to move away from each other, the purpose of such action being to permit such yielding engagement of the bag as will resist the action of the wind and vibrations of the mast and frame, but will be readily overcome by the force of the arm reaching laterally from the passing mail-car. A bracket 9 is attached immovably to the mast. The drawings show said bracket located between the cross-pieces 3 and 4, but the bracket may be located below the cross-piece 4. In the form shown in the drawings

said bracket consists of a hub 10, surrounding the mast, and a set-bolt 11, extending through said hub against the mast, and a standard 12, rising from said hub far enough 5 to bear by its upper end against the lower face of the upper cross-piece 3 when the supporting-frame 2 is at the desired elevation and in the desired plane radial to the mast. All of said bracket is preferably located 10 nearer the mast than is the vertical bar 5, which is adjacent to the arms 6 and 7, in order that the frame may rotate around said bracket, and said standard is at the same time far enough from the mast to permit the 15 cross-piece 3 to descend between the mast and said standard when the supporting-frame has been rotated to stand at right angles to the position which it occupies while holding the bag. (See Fig. 3 and also the dotted outer 20 line of the cross-piece 3 in Fig. 1.)

The operation is as follows: The supporting-frame being in the position shown by Figs. 2 and 3, (at its lower limit and parallel to the railway-track,) the upper end of the 25 bag is secured to the arm 6. Then the lower arm 7 is lifted into the horizontal position and engaged with the lower end of the bag, the weight of said arm serving to maintain engagement of the bag by both the lower and 30 the upper arms. Now by pressing against the lower cross-piece 4 the entire supporting-frame is pushed upward until the upper cross-piece is higher than the upper end of the standard 12. Then the entire supporting-frame is rotated toward the track until the 35 arms stand in a plane radial to the mast and at right angles to the course of the track and the upper cross-piece is directly above or over the standard 12. Then the frame is lowered 40 until the upper cross-piece rests upon the upper end of said standard. When the arm on the mail-car engages the bag, the entire supporting-frame is rotated upon the mast in the direction of the train far enough to release 45 the upper cross-piece from said standard. This leaves said frame free to descend by gravity until arrested by the lower portion of the bracket, and in so descending the frame is guided by said standard 12, so that by the 50 time the frame rests upon the lower portion of the bracket the frame will have been brought into a plane parallel to the track or perpendicular to the plane in which the frame stood before the bag was taken. In said position 55 said frame is held safely out of the range of passing trains.

It is to be observed that the length of the standard 12 may be varied for the purpose of bringing the supporting-frame as low as 60 may be desired to permit the hanging of the bag by a person standing on the ground.

By loosening the set-bolt 11 the bracket 9 may be adjusted vertically or radially upon the mast or together with the supporting-frame entirely removed from the mast for repairing or replacing of parts. This provision for adjustment makes it unnecessary

that the mast be set at a precise elevation or radial position. The mast may be set approximately right and the precise position for 70 the supporting-frame then fixed by a proper setting of the bracket.

In Fig. 4, which is a detail transverse sectional view adjacent to the upper end of the bracket 9, the lower face of the upper cross-piece 3 is shown as having a cavity 3^a for receiving the upper end of the bracket. This construction compels the slight upward movement of the supporting-frame simultaneously with the initial portion of the lateral movement. The resistance to such vertical movement (said resistance being the weight of said frame and the bag) is to be enough to prevent wind, particularly the air-currents caused by the moving train, from moving the frame and 85 bag laterally.

In Fig. 5, which is a section similar to Fig. 4, the upper end of the standard 12 has a central depression in which the upper cross-piece may rest and from which lateral movement can take place only by a preliminary vertical movement of the supporting-frame and the bag. Obviously other means than thus relatively recessing said standard and said frame may be employed for offering resistance to the lateral movement of said frame while the latter rests upon said bracket.

It will be observed that my apparatus is adapted to be operated by a train running in either direction. It will also be observed that 100 when the bag is being taken the supporting-frame yields in the direction of the movement of the train. This reduces strain upon the crane to the minimum.

I claim as my invention—

1. In a mail-bag crane, a vertical mast, a supporting-frame slidably and rotatably secured to said mast and having means for supporting a mail-bag, and means for supporting said frame while the latter is at a certain elevation and in a certain plane radial to said mast and releasing said frame when rotated out of said plane.

2. In a mail-bag crane, a vertical mast, a supporting-frame slidably and rotatably secured to said mast and having means for supporting a mail-bag, and adjustable means for supporting said frame while the latter is at a certain elevation and in a certain plane radial to said mast and releasing said frame 115 when rotated out of said plane.

3. In a mail-bag crane, a vertical mast, a supporting-frame slidably and rotatably secured to said mast and having means for supporting a mail-bag, and means for supporting said frame while the latter is at a certain elevation and in a certain plane radial to said mast and releasing said frame when rotated out of said plane and arresting said frame when the latter reaches a certain lower elevation.

4. In a mail-bag crane, a vertical mast, a supporting-frame slidably and rotatably secured to said mast and having means for sup-

porting a mail-bag, and means for supporting said frame while the latter is at a certain elevation and in a certain plane radial to said mast and releasing said frame when rotated out of said plane and guiding said frame against returning into said plane while said frame is descending by gravity.

5. In a mail-bag crane, a vertical mast, a supporting-frame slidably and rotatably secured to said mast and having means for supporting a mail-bag, and adjustable means for supporting said frame while the latter is at a certain elevation and in a certain plane radial to said mast and releasing said frame when rotated out of said plane and guiding said frame against returning into said plane while said frame is descending by gravity.

6. In a mail-bag crane, a vertical mast, a supporting-frame slidably and rotatably secured to said mast and having means for supporting a mail-bag, and means for supporting said frame while the latter is at a certain elevation and in a certain plane radial to said mast and releasing said frame when rotated out of said plane and guiding said frame into and holding it in a plane perpendicular to the aforesaid plane while said frame descends by gravity.

7. In a mail-bag crane, a vertical mast, a supporting-frame slidably and rotatably secured to said mast and having means for supporting a mail-bag, and adjustable means for supporting said frame while the latter is at a certain elevation and in a certain plane radial to said mast and releasing said frame when rotated out of said plane and guiding said frame into and holding it in a plane perpendicular to the aforesaid plane while said frame descends by gravity.

8. In a mail-bag crane, a vertical mast, a slidably and rotatable supporting-frame consisting of upper and lower cross-pieces, vertical bars, 5, arms, 6 and 7, and means for supporting said frame while the latter is at a certain elevation and in a certain plane radial to said mast and releasing said frame when rotated out of said plane.

9. In a mail-bag crane, a vertical mast, a slidably and rotatable supporting-frame consisting of upper and lower cross-pieces, vertical bars, 5, arms, 6 and 7, and adjustable means for supporting said frame while the latter is at a certain elevation and in a certain plane radial to said mast and releasing said frame when rotated out of said plane.

10. In a mail-bag crane, a vertical mast, a slidably and rotatable supporting-frame consisting of upper and lower cross-pieces, vertical bars, 5, arms, 6 and 7, and means for supporting said frame while the latter is at a certain elevation and in a certain plane radial to said mast and releasing said frame when rotated out of said plane and arresting said frame when the latter reaches a certain lower elevation.

11. In a mail-bag crane, a vertical mast, a slidably and rotatable supporting-frame con-

sisting of upper and lower cross-pieces, vertical bars, 5, and arms, 6 and 7, and means for supporting said frame while the latter is at a certain elevation and in a certain plane radial to said mast and releasing said frame when rotated out of said plane and guiding said frame into a plane perpendicular to the aforesaid plane.

75

12. In a mail-bag crane, a vertical mast, a supporting-frame slidably and rotatably secured to said mast and having means for suspending a mail-bag, and a bracket located upon said mast and rising adjacent to said mast and adapted to support said frame at two different elevations and in a different plane at each elevation.

13. In a mail-bag crane, a vertical mast, a slidably and rotatable frame consisting of upper and lower cross-pieces, vertical bars, 5, and arms, 6 and 7, and a bracket located upon said mast and rising adjacent to said mast and adapted to support said frame at two different elevations and in a different plane at each elevation.

14. In a mail-bag crane, a vertical mast, a supporting-frame slidably and rotatably secured to said mast and having means for suspending a mail-bag, and an adjustable bracket located upon said mast and rising adjacent to said mast and adapted to support said frame at two different elevations and in a different plane at each elevation.

15. In a mail-bag crane, a vertical mast, a slidably and rotatable frame consisting of upper and lower cross-pieces, vertical bars, 5, and arms, 6 and 7, and an adjustable bracket located upon said mast and rising adjacent to said mast and adapted to support said frame at two different elevations and in a different plane at each elevation.

16. In a mail-bag crane, a vertical mast, a slidably and rotatable frame consisting of upper and lower cross-pieces, vertical bars, 5, and arms, 6 and 7, and a bracket located upon said mast between said cross-pieces and rising adjacent to said mast and adapted to support said frame at two different elevations and in a different plane at each elevation.

115

17. In a mail-bag crane, a vertical mast, a supporting-frame slidably and rotatably secured to said mast and having means for suspending a mail-bag, and a bracket comprising a standard and a hub surrounding said mast and means for securing said hub to said mast at different elevations.

120

18. In a mail-bag crane, a vertical cylindrical mast, a supporting-frame slidably and rotatably secured to said mast and having means for suspending a mail-bag, and a bracket comprising a standard and a hub surrounding said mast and means for securing said hub to said mast at different elevations.

130

19. In a mail-bag crane, a vertical mast, a supporting-frame slidably and rotatably secured to said mast and having means for suspending a mail-bag, and a bracket compris-

ing a standard and a hub surrounding said mast and a set-bolt for securing said hub.

20. In a mail-bag crane, a vertical mast, a supporting-frame slidably and rotatably secured to said mast and having means for supporting a mail-bag, and a bracket for supporting said frame while the latter is at a certain elevation and in a certain plane radial to said mast to said mast and releasing said frame when rotated out of said plane, said bracket and the portion of said frame engaging with said bracket being relatively recessed, for the purpose of increasing engagement between said parts.
- 15 21. In a mail-bag crane, a vertical mast, a

supporting-frame slidably and rotatably secured to said mast and having an upper fixed arm and a lower hinged arm for supporting a mail-bag, and means for supporting said frame while the latter is at a certain elevation and in a certain plane radial to said mast and releasing said frame when rotated out of said plane. 20

In testimony whereof I have signed my name, in presence of two witnesses, this 28th 25 day of April, in the year 1903.

JOHN M. C. HOWELL.
